[57] CLAIM

The ornamental design for a pallet nut, as shown and
described.

DESCRIPTION

FIG. 1 is a perspective view showing my pallet nut;
FIG. 2 is a side elevation view thereof on a reduced
scale, the pallet nut being symmetrical about its central
longitudinal axis;

FIG. 3 is a top plan view thereof on a reduced scale; and
FIG. 4 is a bottom plan view thereof on a reduced scale.

FIG. 1

FIG. 2

FIG. 3

FIG. 4
